(57) CLAIM

The ornamental design for an automobile front bumper, as shown and described.

DESCRIPTION

FIG. 1 is a perspective view of the exterior surface of the front and right sides of the automobile front bumper of the invention, the left side of the front bumper being identical to the right side of the front bumper, the interior surface having no ornamentality;

FIG. 2 is a top plan view of the exterior surface of the front bumper illustrated in FIG. 1, the interior surface having no ornamentality;

FIG. 3 is a side view showing the exterior surface of the right side of the front bumper illustrated in FIG. 1, the left side of the front bumper being identical to the right side of the front bumper, the interior surface having no ornamentality; and, FIG. 4 is a front view of the exterior surface of the front bumper illustrated in FIG. 1, the interior surface having no ornamentality.

The broken lines shown in all drawing views are for illustrative purposes only and form no part of the claimed design.
